UNITED STATES PATENT OFFICE.

JOHAN LUGER, OF CLARKE COUNTY, OHIO.

VENT FOR CASKS.

SPECIFICATION forming part of Letters Patent No. 244,396, dated July 19, 1881.

Application filed May 28, 1881. (Model.)

To all whom it may concern:

Be it known that I, JOHAN LUGER, of the county of Clarke and State of Ohio, have invented a new and useful Improvement in Vents for Fermented Liquors in Casks, of which the following is a specification.

My invention relates to an air-vent for fermented liquors, which can be applied either to the bung or to the body of the cask.

10 My invention further relates to a vent which is of simple construction, easily applied, and which embodies in a single device separable parts which admit of connection and adjustment for its application to the bung of a cask, 15 or to the staves or head of the same.

Figure 1 is a vertical section of a bung inserted in a section of a cask, with an axial section of my improved vent applied thereto. Fig. 2 shows a section of the stave and head 20 of a cask, with another portion added to the vent-pipe, which is also shown in axial section. Fig. 3 shows two views of a vent-pipe used with bungs, as shown in Fig. 1, without the end cap. Fig. 4 is an end view of the cap. 25 Fig. 5 is a vertical section of the same (enlarged) with the ball therein.

The object of my invention is to produce a vent for casks containing fermented liquors, which can be made cheap, which can easily 30 be removed and cleansed, is not liable to get out of order, and which can be applied to either the bung or the body of the cask.

A is the bung. B' is the section of a beer-cask; B, the vent, consisting of an elbow-pipe, 35 a, and a cap, c, which is screwed upon the end which turns downward. a' is a hole in the middle of the bung, communicating with the interior of the cask through the vent-pipe. The sections of the vent-pipe are threaded, to 40 make them fit snugly together gas-tight. One end of the pipe screws into the hole a' in the bung, and the other end, which is formed into an elbow, is also threaded to receive the end cap c. A plain hole extends through the pipe-section a, which is free, except at the outer 45 end of the elbow, as seen in the view of the end d, Fig. 3, where a bar, c', is seen across the hole. The object of this bar is to prevent the ball i in the chamber e of cap c from es- 50 caping into the part a when the latter is in-

verted, or when the air-current carries the ball away from its seat over the hole e'. In whatever position the vent is applied the cap c must be in a vertical position, as shown in Figs. 1, 2, and 5, the latter of which shows the 55 normal position of the ball.

Fig. 2 shows the vent applied through the stave S of a cask, a hole being first bored through the same and the end of the long arm screwed therein. In this vent there are three 60 sections—pipe a, which is placed vertically; b, another elbow-section, which is screwed on the horizontal short limb a'' of a, and the cap c. In case the user should desire to apply this vent to the bung A, the interposed middle section, b, is taken off, the cap c screwed upon the end of a, and the vent applied as seen in Fig. 1. The bung can be first driven and plugged, or the vent first inserted, as the parts are not liable, from the shock of driving, 70 to get out of place. The bar c' is made in the outer end of both sections a and b, so that the ball i cannot escape from the inverted conical chamber e in the cap c. Both the cap c and the section b are provided with an interior 75 threaded end, to adapt them to fit upon the limb a'' of pipe-section a. The size of the ball i (see Fig. 5) is very small in proportion to the chamber e of the cap and the diameter of the pipe. The hole e' is also very small, being 80 but about one-sixteenth of an inch in diameter in the full-sized vent. A No. 8 bird-shot is used for the ball.

The operation of my improved vent is very 85 easily understood. As the gas is drawn off from the beer the air enters the vent through the small hole e' and sends the ball spinning around the chamber e, finally settling over the hole e' in the apex of the chamber after sufficient air is admitted through the vent.

I am aware that vents have been constructed with air-chambers, valves, &c.; but I do not claim them, as their construction entails heavy cost and their adaptability is limited.

In nearly all beer-vents their complex arrangements and cost prevent their common use. In my device I have adopted the most simple means at the least cost.

I claim as my invention—

1. In a vent for casks containing fermented

liquors, the combination, with an elbow pipe section, of a screw-threaded cap fitted thereto, and having an interior inverted conical chamber terminating in a fine hole and containing a small ball or shot, whereby the passage of air is regulated in passing through said vent, substantially as described.

2. A vent for a cask containing fermented

liquor, consisting of the elbow-pipe *a* with the bar *c'*, the screw-threaded cap *c*, and a small ball or shot, *i*, substantially as set forth.

JOHAN LUGER.
